(57) **CLAIM**

The ornamental design for a plumbing fitting, as shown and described.

DESCRIPTION

In a preferred embodiment, the nature of this product is as a plumbing fitting in the form of a faucet with a movable spray head usable to wash various items and/or body parts, as well as a handle and a spray head therefor.

FIG. 1 is a right, top, front perspective view of a plumbing fitting embodying our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken lines are included for the purpose of illustrating portions of the plumbing fitting that forms no part of the claimed design.
